LAMP CHIMNEY FORMING MACHINE

Earl S. Brunson, Elwood, Ind.

Application May 26, 1932. Serial No. 613,762

3 Claims. (Cl. 49—27)

This invention relates to machines for use in the forming or manufacture of lamp chimneys and pertains particularly to a machine for forming a welt or bead around the bottom part or heel of the chimney.

The primary object of the present invention is to provide a machine to facilitate the forming of a bead or welt around the base or heel portion of the chimney easily and quickly and to supplant 10 the old method of forming the tubular base by hand.

Another object of the invention is to provide a machine which, after a suitable glass bulb has been blown while the glass is carried upon the punt, may be caused to operate upon the bulb to open the same and form the cylindrical base or heel portion of a lamp chimney and the bead at the upper part of the base against which the 15 ends of the supporting members or prongs of a lamp engage when the chimney is in use.

A still further object of the invention is to provide a machine for the above described purpose in which a novel means is employed for piercing the glass ball or bulb of which the chimney is to 20 be formed, and for spreading the bulb about the pierced area to form the lamp chimney base.

The invention will be best understood from a consideration of the following detailed description taken in connection with the accompanying 25 drawing forming part of this specification, with the understanding, however, that the invention is not confined to any strict conformity with the showing of the drawing but may be changed or modified so long as such changes or modifications 30 mark no material departure from the salient features of the invention as expressed in the appended claims.

In the drawing:

Figure 1 is a view in longitudinal section 40 through the mechanism embodying the present invention with parts associated therewith in side elevation;

Figure 2 is an enlarged sectional detail taken longitudinally of the front end of the machine 45 in a plane at right angles to the plane of the section thereof, as shown in Figure 1;

Figure 3 is a transverse section taken on the line 3—3 of Figure 1;

Figure 4 is a transverse section taken on the 50 line 4—4 of Figure 1.

Referring now more particularly to the drawing wherein like numerals of reference indicate corresponding parts throughout the several views, the numeral 1 indicates a table or other suitable 55 support upon which the mechanism embodying

the present invention is mounted, this table having suitable supporting legs 2.

Mounted upon the table in axial alignment are a pair of spaced annular bearings 3 each of which is provided with a suitable base 4 to facilitate its secure attachment to the table and through these bearings there extends the cylinder body 5 which is provided with peripheral grooves or channels 6 in each of which a ring bearing 3 engages. Mounted upon the cylinder 5 is a gear 5' by 60 means of which power connection may be made with the cylinder to effect its rotation.

The ends of the cylinder 5 are closed by the plates 7 and 8 and the plate 8 as shown, has a central opening 9 therein which communicates 70 with the circular interior of the tubular extension 10 which forms an integral part of the plate 8 as shown. This extension 10 of the cylinder plate is provided with the longitudinally extending slots 11 at diametrically opposite points as 75 illustrated, and portions of these slots open entirely through the wall of the extension, the forward ends thereof tapering off in the inner surface of the extension wall, as illustrated.

Secured in any suitable manner to the open 80 forward end of the extension 10 of the cylinder is a plate 12 which has a vertical slot 13 therethrough and a short lateral slot 14 which communicates with the slot 13 at a point midway between the ends of the latter. This plate 12 85 forms a head for the outer end of the tubular extension 10 and integral with it there is formed the band or ring 15, the inner surface of which is flush with the ends of the slot 13.

The slot 13 of the head plate 12 is vertically 90 arranged in the same vertical plane as the slots 11 in the tubular extension and secured in the opening 9 are the ends of a pair of elongated resilient arms 16 which extend forwardly in convergent relation through the extension and 95 through the slot 13 in the head 12, the forward ends of these arms being tapered and in contacting relation to form when together the point or spear 17 which is disposed upon the longitudinal center of the machine. As illustrated the 100 rear ends of the forwardly converging arms 16 are located in the slots 11 and when the arms are sprung apart as will be hereinafter more fully described they move outwardly into the slots 11. As is also shown, the point 17 extends a substantial distance beyond the head 12 and the ring 15 which it carries.

Suitably mounted upon the head 12 as by the supporting ears 18, is an oscillating former or 110 presser body 19. This body is relatively long and

arcuately shaped as shown and has one end pivotally attached to the ears 18 and extends through the slot 14 of the head and forwardly beyond the free edge of the band 15 as illustrated in Figure 3.

Within the cylinder 5 there is mounted a relatively long piston body 20 through which extends a rod 21, the forward end of which passes through the opening 9 of the plate 8 and carries the head 22 which is located in the tubular extension 10 and between the resilient arms 16. The other end of this rod 21 passes through the opposite end plate 7 and is secured in the upturned angular extension 23 of an actuating rod 24 which is reciprocably mounted in the supports 25 at the under side of the table 1.

Surrounding the rod 21 between the upturned end 23 of the actuating rod and the plate 7 of the cylinder, is a coil spring 26 which normally shifts the rod and head 22 rearwardly in a retracted position with respect to the convergent ends of the resilient arms 16.

At the forward end of the table 1 there is located in a suitable floor support 27, one end of a foot lever 28 which is connected by a link 29 with one arm of a bell crank lever 30 mounted in a suitable position for oscillation in a vertical plane, as for example, upon the bracket 31 mounted upon the forward leg 2 of the table. The other arm of the bell crank lever 30 has pivotal connection with the forward end of the pull rod 24.

Upon the top of the table there are mounted two supporting members each of which is indicated by the numeral 32, the tops of which are suitably formed to support the tube 33 employed by glass blowers and known as a punt. This tube is employed for picking up a ball of glass and for blowing air into the ball to form the same into a bulb.

In the operation of the present machine a suitable bulb is formed upon the end of the punt 33 in the usual manner and the punt is then disposed across the upper ends of the supports 32 in the manner illustrated. The supports 32 are at the proper height to locate the longitudinal center of the punt upon the longitudinal center of the tubular extension 10 and the cylinder 5 so that when the punt is shifted longitudinally toward the point 17 this point will enter the center of the bulb. The movement of the bulb is continued until it is brought into position against the head 12. The forward end of the former member 19 will also enter the bulb.

After locating the glass bulb in the manner described the foot lever 28 is depressed so as to cause the rod 21 and head 22 to move forwardly and expand the arms 16 and consequently separate the tapered forward ends thereof and the cylinder 5 and parts carried thereby is also rotated so that as the pointed ends of the arms are separated they will smooth out the interior of the bulb against the inner face of the ring 15 and thus form the cylindrical base portion 35 of the lamp chimney. Continued forward movement of the head 22 will bring the same into contact with the rear end of the oscillatably mounted former 19 and cause the free forward end to be swung outwardly to extend beyond the forward edge of the sleeve 15 and consequently press a portion of the glass bulb outwardly. After the former 19 has been moved to this position it will be readily apparent that upon continued rotation of the cylinder and the parts carried thereby which includes the former and the arms 16,

the end of the former will move about the interior of the bulb and cause an outwardly pressed bead to be formed thereabout at the upper end of the straight cylindrical heel portion formed by the arms 16.

The lower part of a chimney is shown in position upon the forward end of the tubular part 10 of the machine and is indicated by the numeral 34, the cylindrical base part being indicated by the numeral 35 and the bead by the numeral 36.

From the foregoing it will be seen that in a machine of the character herein described the base and bead portion of a lamp chimney may be easily and quickly formed and the base will be a perfect circle and of even thickness throughout.

By mounting the rod 21 upon the reciprocable piston body 20 the rod is caused to move forwardly without deviation from the longitudinal center of the tubular extension in which the head at the forward end thereof moves and as will also be readily apparent upon the release of the foot lever the spring 26 will operate to retract the rod 21 so as to permit the tapered ends of the resilient arms 16 to resume their former positions.

Having thus described the invention, what is claimed is:—

1. A base forming device for a lamp chimney, comprising an annular body into which a glass bulb is inserted to be shaped into the chimney base, means coacting with the annular body for shaping the inner surface of the lamp base, said annular body and said means being rotatable, means pivotally carried by and normally projecting from the annular body for engaging the interior of the glass bulb to shape an outwardly pressed bead therein upon the rotation of the body, and means operating to first actuate said first means and then swing said pivotally carried means into operative engagement with the bulb.

2. A machine for forming a cylindrical end upon a plastic bulb of glass from which a lamp chimney is formed, comprising a cylinder, means for rotatably supporting the same, a tubular extension at one end of the cylinder, a rod extending axially through the cylinder and having a head at one end located in said tubular extension, an annular former member secured to and coaxial with the tubular extension, a plate closing an end of the former member and constituting a head for the end of the tubular extension, said plate having a slot therein, a pair of arms disposed within the tubular member and arranged in outwardly convergent relation and having the convergent ends extending through the slot in said plate, the head of said rod when shifted toward the outer end of the tubular extension separating the convergent ends of said arms, means reciprocable within the cylinder for carrying said rod, means for effecting the reciprocation of the rod and the head carried thereby, and an elongated finger member oscillatably secured to said plate and having one end extending beyond the annular former member, the said head of the rod being designed to oscillate said finger to extend the said end thereof outwardly radially of the annulus for the formation of an out-pressed bead in the wall of the glass bulb from which the lamp chimney is shaped.

3. A lamp chimney forming machine, comprising a rotatable hollow cylindrical body, a cylindrical member secured against one end of the cylindrical body concentrically therewith and having a plate closing the end abutting the cylindrical body, said plate having a slot therein, a

pair of elongated arms secured to the cylindrical body adjacent the end opposite the cylindrical member and having the other ends passing through said slot and the cylindrical member and converging at a point a substantial distance beyond the member, said arms being of a resilient character, means reciprocable in the rotatable body for spreading the convergent ends of the arms apart to shape a lamp chimney base against the inner surface of the cylindrical member, and 10 an arcuate arm pivotally attached at one end to

the inner wall of the rotary member and extending through said slot and the cylindrical body to a point outside of the latter and terminating at its free end in a head, said arcuate arm being swung about its pivot by the arm separating means after the arms have been separated to the limit of their movement to project the head across the outer end of the cylindrical member for the formation of a bead in the lamp chimney base. 80 85
